UNITED STATES PATENT OFFICE.

WILSON P. JOHNSON, OF COLUMBUS, OHIO.

MANTLE-SUPPORT.

SPECIFICATION forming part of Letters Patent No. 757,556, dated April 19, 1904.

Application filed February 2, 1904. Serial No. 191,681. (No model.)

To all whom it may concern:

Be it known that I, WILSON P. JOHNSON, a citizen of the United States, residing at Columbus, in the county of Franklin and State of Ohio, have invented certain new and useful Improvements in Mantle-Supports; and I do hereby declare the following to be a full, clear, and exact description of the invention, such as will enable others skilled in the art to which it applies to make and use the same.

A great deal of expense and annoyance have been occasioned by the destruction of Welsbach mantles due to the softening and bending of the support for holding them.

The object of the present invention, therefore, is to provide a support in which this trouble cannot occur; and the invention consists in the construction hereinafter described and claimed.

In the accompanying drawings, Figure 1 is a view in vertical elevation of a burner and chimney-frame equipped with my device. Fig. 2 is a top plan view. Fig. 3 is a side view of the yoke-like bridge upon which the mantle is hung. Fig. 4 is an end view of the same. Fig. 5 is a bar for supporting the bridge.

In the views the bridge portion proper is, generally speaking, of U form—that is, having a horizontal portion 1 with a middle seat 1^a to receive the loop of the mantle and upright portions 1^b at its ends. The upright portions are made each with a series of holes 1^c, through a horizontal pair of which is passed a rod 2, so that its ends shall project beyond the upright portions, as seen in Figs. 1 and 2.

When the mantle is in place in the frame, the ends of the rod 2 rest on the upper side of the top ring 3 of the frame, as seen in Fig. 1.

The bridge proper and the rod will preferably be made of magnesia, clay, or other material refractory to heat. The bridge can be made of metal and the rod of the refractory material with good results; but in this event it will be desirable to cover the horizontal portion with asbestos, as indicated at 4 in Fig. 1.

Besides the advantages of adjustability and firmness of the support it will be observed that the light from the mantle in a horizontal or downward direction is not in any measure obstructed by the support.

What I claim, and desire to secure by Letters Patent, is—

1. In a mantle-support, the U-shaped bridge having perforated upright arms, in combination with a bar to engage the perforations of said arms and extend beyond the same.

2. In a mantle-support, the U-shaped bridge having a horizontal portion with a seat for the loop of the mantle and perforated upright arms, in combination with a bar to pass through said perforations and project beyond the arms.

In testimony whereof I affix my signature in presence of two witnesses.

WILSON P. JOHNSON.
